UNITED STATES PATENT OFFICE.

BERNARD MARKOW, OF BROOKLYN, NEW YORK.

BIRD CAGE AND THE CONSTRUCTION THEREOF.

Application filed April 15, 1927. Serial No. 183,937.

This invention relates to bird cages and to the construction thereof and particularly to the means for securing the cage wires in place, to the door mounting and to the method of 5 making the cage body. The invention is especially applicable to cages in which the wires are held apart in relation by means of horizontal bands. In carrying out my invention I contemplate the production of predetermined lengths of wire cage body units held together by suitable spaced bands, and of the proper dimensions for the formation of individual cages. After the length or unit has been made the ends of the bands of each unit 10 are brought together and secured by a clamp to produce the cage body. I further contemplate the provision of means on certain of said clamps for supporting and guiding the cage door and for limiting the movement of 15 said door in either direction.

The various objects of my invention will be clear from the description which follows and from the drawings, in which,

Fig. 1 is a front elevation of a cage constructed in accordance with my invention.

Fig. 2 is a perspective view of a portion of one of the bands for holding the wires in place.

Fig. 3 is a similar view of a portion of the 30 lowermost band of the cage and of a clamp for securing the ends of the band in place.

Fig. 4 is a similar view of the combined clamp and door guide preferably used for the upper band of the cage.

Fig. 5 is a similar view of the clamp for the intermediate band which also serves as a door stop, and

Fig. 6 is a similar view of part of the band forming the lowermost part of the cage door and of the guiding means for the door.

In carrying out my improved method, I provide the upper band 10, the intermediate band 11 and the lowermost band 12 of the cage, which are preferably formed of flat sheet metal strips all of preferably the same size and provided with suitable holes as 13 in the desired spaced relation for the reception of the cage wires 14. The flat perforated blanks are then formed into channels wherein the flanges contain the holes 13 and the wires 14 are passed completely through the holes in both flanges of each of the bands 10 and 11. In the case of the lowermost band 12, the cage wires are passed through the holes in the upper flanges of the channel and down to the lower flange, the holes being

so arranged that the most forwardly parts thereof are in alignment with the inner face of the channel web so that the wires may contact with said face without distortion. The 60 flat sheet 15 which is preferably of less width than that of the channel web of the partly formed band is then laid over the wires 14, after which the edge portions of the flanges are bent towards each other and pressed into 65 close contact with the sheet 15 whereby the band is bent substantially into the form of a flattened elongated tube. These operations may be performed continuously or in desired 70 lengths whereby a structure results in which 75 a series of spaced wires are held together by the various bands, in which the strip 15 and the portions of the wires held thereby retain their original size and shape and the front and rear of the bands are arranged parallel 80 with the strip 15 so that none of the parts are mutilated or distorted.

When it is desired to form an individual cage, a length equal to the perimeter of the 85 finished cage is pressed about a block of the desired shape or otherwise formed into shape and the bands are bent to the proper shape without mutilation of the wires, the free ends of the length being brought together, 90 whereby a cage body of any desired polygonal shape results. For providing the door opening, the wires 14 between the bands 10 and 11 may be severed close to said bands, but I prefer to arrange the opening so that the 95 free ends of the bands 10 and 11 form the upper and lower ends thereof respectively. For securing the free ends of the band 10 in position, I provide the clamp 16 of sheet metal bent into substantially tubular form and provided with suitable slots as 27 adapted to become finally arranged on the inside 100 of the cage with the wires 14 at the extremities thereof whereby the clamp may clear the wires without interference, and the slots are substantially unnoticeable. In bending the clamp 16 about the band 10 (Fig. 4) I prefer to form the fold or flange 17 of two thicknesses of material, projecting forwardly of the cage and provided with the perforations 105 18 through which the wires 19 of the cage door 20 may be passed. It will be seen that the clamp 16 serves not only to secure the otherwise free ends of the band 10 in place but serves the additional function of a support and guide for the wires of the cage door. Similarly the clamp 21 (Fig. 5) is used to 110 hold the otherwise free ends of the band

11 in position and is provided with a substantially horizontal flange 22 similar to the flange 17 and serving as a platform to limit the movement of the cage door in the same manner as the flange 17 limits the upward movement of said door, said clamps preferably forming the uppermost and lowermost extremities of the door opening.

19 In order to reduce the construction of the cage door 20 to its simplest form without loss of efficiency, I prefer to construct said door of a number of spaced parallel cage wires 19 of the proper length, which length is slightly greater than the height of the door opening 23, and I secure said wires in position by a band 24 arranged preferably at the lowermost ends of the wires, and similar in all respects to the band 12. At the extremities of the band 24 I provide the door guides 25 each formed preferably of a single sheet of material and having a portion thereof bent into close contact with and about the outer surface of the end of the door band 24. Projecting from the front face of the guide 25 and preferably integral therewith is the hook member 26, which is preferably cylindrically shaped to pass about and engage those wires 14 of the cage which are immediately adjacent to the cage door opening 23.

30 It will be seen that the door 20 may be opened simply by lifting it, in which case the wires 19 thereof are maintained in position by the perforations 18 of the clamp 16 while the hook members 26 engage certain of the wires 14 and prevent transverse and lateral movement of the door out of its proper position. The flange 17 of clamp 16 serves as a stop to limit the uppermost position of the door while the flange 22 of the clamp 21 serves similarly to limit the lowermost position of the door.

45 It will further be seen that I have provided an improved method for making wire structures of the type described and have further provided an improved means consisting of the various bands for holding the cage wires firmly in permanent spaced relation without detracting from the good appearance of the structure. It will also be seen that I have 50 provided a novel cage door mounting which serves the additional function of securing the free ends of the various bands permanently in place.

55 It will be understood that various changes in the embodiment of my invention illustrated herein may be made without departing from the spirit of this invention and the scope of the appended claims.

I claim:

60 1. In a bird cage structure, a series of wires, and a band enclosing straight portions of said wires and frictionally holding said wires in predetermined horizontal spaced relation, comprising a substantially closed flattened tube having a series of spaced apertures

in the narrowest part thereof of the cross-sectional shape of and adapted to receive said wires, the wide faces of said tube being parallel throughout and the least depth of said tube measured from front to rear being greater than the diameter of said wires, and a strip parallel throughout to the faces of said tube and arranged in the interior of the tube between said wires and the rear face of the tube and clamped by the tube in engagement with the wires while the parallelism of the strip and the tube is maintained.

2. In a bird cage structure, the combination with a series of wires, of means for maintaining said wires in spaced relation comprising a flattened elongated tube of a strip of sheet material bent with the peripheral edges thereof unmutilated and arranged in close proximity and having perforations therein spaced from said edges for the passage of said wires therethrough, and a strip of sheet material entirely within the interior of said tube between said wires and the inner rear face of said tube, said strip, the axes of the portions of said wires within said tube, and the front and rear walls of said tube, being substantially parallel, unmutilated and undistorted.

3. In a bird cage structure, cage wires, and means for frictionally engaging undistorted portions of said wires for maintaining said wires in transverse spaced relation comprising an unmutilated and undistorted strip engaging said wires, a band, passed about said wire portions and on to said strip for substantially completely enclosing said strip and forcing said strip into pressed contact with said wire portions, and having perforations spaced from the peripheral edges thereof, and adapted to have wires passed through said perforations into the interior thereof, and means for clamping the otherwise free ends of said band in place.

4. In a bird cage structure, a series of wires, a tubular band adapted to maintain said wires in transverse spaced relation and means for securing the adjacent ends of said bands in place comprising a strip of sheet material passed about and substantially enclosing the end portions of said band and having slots therein extending inwardly from one of the edges thereof at the ends of which slots are arranged the end wires of said band.

5. In a bird cage structure, cage wires, a band adapted to receive and clamp said wires in place, and a clamping member of less length than that of said band arranged about said band and having slots therein in registration with said wires and in which said wires are arranged.

6. In a bird cage structure, including banded wires and having a door opening therein, a combined clamp and door support comprising a slotted clamping member the length of which is equal to the width of said opening, and substantially enclosing the

banded portions of the wires adjacent to said opening, and a folded flange of two thicknesses of material extending from the remainder of said support.

5 7. In a bird cage structure, including bands for holding the cage wires in place, a clamp for said bands, of sheet material having spaced slots extending from one of the peripheral edges thereof toward the other edge and bent into substantially flattened and elongated tubular form about the ends of each of said bands, with the cage wires of the band ends passing through said slots.

10 8. In a bird cage structure, a combined clamp and door guide of sheet material bent substantially into a flattened elongated tube and a perforated flange extending from said clamp, adapted to have the wires of a cage passed therethrough.

15 9. In a bird cage structure, a clamp for the otherwise free ends of the cage bands, comprising a piece of sheet material, having transverse spaced slots therein, and bent into substantially tubular form about said free ends, and a flange projecting from the upper surface of the tubular portion of said clamp.

20 10. In a bird cage structure having an opening for a door therein, a pair of tubular bands of predetermined length, each of said bands being arranged respectively at the upper and lower extremities of the door opening, a clamp for the ends of the upper of said bands and door guide combined, comprising a sheet of material bent to substantially 25 enclose the ends of the upper band and a horizontal perforated flange bent from said sheet, and a combined clamp and door stop similarly bent about the ends of the lower band, and having a horizontal flange extending therefrom in substantial alignment with the flange of said combined clamp and door guide.

30 11. In a bird cage structure having an opening for a door therein, cage wires, means for holding said wires in spaced relation comprising a pair of perforated bands, into which said wires are passed, and arranged at the upper and lower end of the door opening respectively, in contact with said wires at the front thereof, and a strip in each of said bands in contact with said wires at the rear thereof, each of said bands being bent into flattened tubular form about said strip and said wires, the ends of said bands being arranged at said openings, and clamps of sheet material, each having a projecting flange thereon arranged about said bands across said opening for securing the ends of said band in place and limiting the vertical movement of a door in said opening.

35 12. In a bird cage structure, having an opening for a door therein, cage wires, a pair of bands for holding said wires in spaced relation arranged respectively at the upper and lower ends of said opening, and with

their free ends at said opening, and clamps for securing the ends of said opening, each of said clamps having a flange projecting beyond the remainder thereof for limiting the movement of a cage door in said opening. 70

13. In a bird cage structure, cage wires, a cage door comprising a plurality of vertical wires, means at the lower ends of the door wires for holding said wires in spaced relation, hooked members secured to the ends of the wire holding means and adapted to engage and slide on the cage wires for guiding said door, a door guide member having a perforated flange therein for the reception of the door wires and for limiting the movement of the door in one direction, and a flanged member in spaced relation to the door guide member for limiting the movement of the door in the opposite direction. 75

14. A door adapted to slide in the door opening of a bird cage comprising a plurality of parallel wires, a band receiving one end of each of said wires for maintaining said wires in place, and door guide members each having a tubular portion substantially enclosing an end portion of said band and a hook portion, adapted to slide on a cage wire, projecting from the tubular portion. 80

15. In a bird cage structure having an opening for a door therein, cage wires, bands for holding said wires in place, a clamp at one end of said opening having a perforated flange projecting therefrom and engaging one of said wire holding bands, a second clamp at the other end of said opening having a flange 95 projecting therefrom, and a cage door comprising wires passed through the perforations of the first mentioned clamp, a band for holding the door wires in place and for resting against the said mentioned clamp in the closed position of the door, and hooked members on the ends of the door band engaging the cage wires adjacent to said opening. 100

16. The process of constructing a bird cage body consisting of perforating a strip of metal forming said strip into channel form with the most forwardly parts of the perforations in alignment with the inner surface of the web of the channel, passing wires through the perforations, placing a flat strip over the wires, and bending the flanges of the channel down on to said strip under pressure to cause said strip to press said wires between it and the channel web while maintaining the wires and the strip undistorted. 110

17. The process of constructing a bird cage body consisting of perforating a strip of metal forming said strip into channel form with the most forwardly parts of the perforations in alignment with the inner surface of the web of the channel, passing wires through the perforations, placing a flat strip over the wires, bending the flanges of the channel down on to said strip under pressure to cause said strip to press said wires between 115 120 125 130

it and the channel web while maintaining the wires and the strip undistorted, cutting off predetermined lengths of the bands thus formed, and bending the bands into the required shape laterally thereof.

18. The process of constructing a bird cage body consisting of perforating a strip of metal forming said strip into channel form with the most forwardly parts of the perforations in alignment with the inner surface of the web of the channel, passing wires through the perforations, placing a flat strip over the wires, bending the flanges of the channel down on to said strip under pressure to cause said strip to press said wires between it and the channel web while maintaining the wires and the strip undistorted, cutting off predetermined lengths of the bands thus formed, bending the bands into the required shape laterally thereof, and passing a clamp-

ing band about the free ends of the cage bands.

19. The process of constructing a bird cage body consisting of perforating a strip of metal forming said strip into channel form with the most forwardly parts of the perforations in alignment with the inner surface of the web of the channel, passing wires through the perforations, placing a flat strip over the wires, bending the flanges of the channel down on to said strip under pressure to cause said strip to press said wires between it and the channel web while maintaining the wires and the strip undistorted, cutting off predetermined lengths of the bands thus formed, and bending the bands into the required shape laterally thereof, passing a clamping band about the free ends of the cage bands and shaping and converging one end of each of the cage wires.

BERNARD MARKOW.
